NORMAL PARAFFIN ISOMERIZATION WITH
LIQUID PHASE AsF_5/HF CATALYST
John R. Norell, Bartlesville, Okla., assignor to
Phillips Petroleum Company
No Drawing. Filed Dec. 30, 1971, Ser. No. 214,400

ABSTRACT OF THE DISCLOSURE

Normal paraffins are isomerized to skeletal isomers containing the same number of carbon atoms by contacting paraffins with a liquid mixture of arsenic pentafluoride (AsF_5) and HF. For extended reaction periods, hydrogen is employed to suppress cracking.

This invention relates to hydrocarbon conversion. In accordance with another aspect, normal paraffins are isomerized to skeletal isomers containing the same number of carbon atoms by contacting the paraffins with a liquid mixture of AsF_5 and HF. In accordance with a further aspect, cracking of hydrocarbon feed is suppressed during isomerization of normal paraffins in the presence of a liquid phase AsF_5/HF catalyst by the addition of hydrogen. In accordance with a further aspect, an isomerization catalyst comprising liquid phase AsF_5/HF is provided. In accordance with a further aspect, this invention relates to an improved continuous process for the skeletal isomerization of normal paraffins in the presence of a liquid phase AsF_5/HF catalyst by spraying the reactant paraffin into a column of the liquid catalyst.

It is well known that the more highly branched isomers of the paraffinic hydrocarbons occurring in petroleum gasoline fractions are more valuable than the corresponding slightly branched or straight chain hydrocarbons because of their higher octane ratings. The demand for motor fuels of greater octane number has increased markedly as the automotive industry has provided gasoline engines with increasingly higher compression ratios to attain greater efficiency. One of the economically important ways in which the increased demands for high octane fuels can be met is through the isomerization of the light naphtha components of such fuels.

It may be generally stated that the isoparaffinic and branched chain paraffin hydrocarbons are of greater commercial value to the petroleum industry than the corresponding straight chain hydrocarbons. Thus, for example, 2,2-dimethylbutane has a higher octane rating than the isomeric normal hexane. Isobutane is more valuable than normal butane since the former can be used as a basis for the preparation of 8-carbon-atom, branched-chain-hydrocarbons by alkylation with butylene.

The isomerization of normal paraffin hydrocarbons into the corresponding branched chain homologs is well known. For effecting the isomerization, it is customary to employ certain metal halides, particularly aluminum chloride or aluminum bromide, in conjunction with certain promoters such as hydrogen chloride, hydrogen bromide, or boron fluoride. Recently, strong acid systems such as solutions of fluorosulfonic acid and antimony pentafluoride have also been disclosed as useful isomerization catalysts. An important problem arising with the use of these highly active catalysts is that they promote side reactions such as cracking and disproportionation. These side reactions are particularly evident at high conversion conditions and lead to the formation of substantial amounts of undesirable light and/or heavy side products.

In accordance with the invention, the formation of undesirable side products in the isomerization of normal paraffin is substantially reduced by conducting the reac-

2

tion in the presence of a liquid phase AsF_5/HF catalyst. It has been further found that the use of hydrogen pressure during isomerization inhibits cracking and favors isomerization, especially during extended reaction periods.

Accordingly, an object of this invention is to provide an improved isomerization process.

Another object of this invention is to provide an isomerization process whereby formation of undesirable side products during isomerization is minimized.

A further object of this invention is to provide an improved catalyst for isomerization.

Other objects and aspects as well as the several advantages of the invention will be apparent to those skilled in the art upon further consideration of the specification and the appended claims.

In accordance with the invention, it has been found that a liquid phase mixture of arsenic pentafluoride and anhydrous hydrogen fluoride (AsF_5/HF) isomerizes normal alkanes to branched isomers containing the same number of carbon atoms with a minimum formation of undesirable side products during isomerization.

Further according to the invention, it has been found that the use of hydrogen pressure in the range 30-200 p.s.i.g. inhibits cracking and favors isomerization.

In accordance with one specific embodiment, n-hexane isomerizes to predominantly neohexane at room temperature in the presence of AsF_5 and liquid HF.

In accordance with another embodiment, normal butane is readily isomerized in high conversion with high selectivity to isobutane.

Arsenic pentafluoride presents advantages over other superacid catalysts in that it provides a reaction rate significantly higher than those previously known. Additionally, normally n-butane is difficult to isomerize and requires higher temperatures and pressures but utilizing the catalysts of the invention high conversion and high selectivity are obtained at ambient conditions.

Suitable feeds for the purposes of the present invention will contain normal paraffinic hydrocarbons having from 4 to 7 carbon atoms in the molecule and may be exemplified by normal butane, normal pentane, normal hexane, and the like. While the feed may substantially comprise a purified normal paraffinic hydrocarbon stream, it is also contemplated that mixtures of various paraffinic hydrocarbons can be employed.

Arsenic pentafluoride, AsF_5 (M.P.—79.8° C., B.P.—53.2° C., M.W. 169.9), is a known compound and is commercially available and is readily dissolvable in liquid HF at room temperature. Any other procedure for combining arsenic pentafluoride and liquid HF to form the catalysts of the invention can be employed, as desired.

The mole ratio of liquid HF/ AsF_5 forming the catalysts of the invention will generally be in the range 400:1 to 1:1, preferably 20:1 to 100:1. The mole ratio of normal paraffinic hydrocarbon to AsF_5 will generally be in the range 50:1 to 0.2:1, preferably 1:1 to 20:1.

The reaction conditions for isomerization of the feed can be in the range of 0 to 100° C., usually 15 to 65° C., and pressure sufficient to maintain the hydrocarbon reactants and catalysts as liquids in the reaction zone and the temperatures and pressures should be chosen accordingly. The time of contact is subject to wide variation, the length of residence time dependent in part upon the temperature and catalyst concentration employed. In general, contact times ranging from about 5 minutes to 48 hours, preferably 15 minutes to about 2 hours, are employed.

As indicated above, the formation of undesirable side products can be suppressed by carrying out the isomerization in the presence of at least 30 p.s.i.g. of hydrogen pressure. The hydrogen pressure can vary from 0 to 400 p.s.i.g., but when employed will preferably range from 30 to 200 p.s.i.g. For reaction periods exceeding about 60

minutes, it is desirable to employ hydrogen pressures in the preferred range in the catalyst system to suppress cracking reaction.

The process of the invention is conducted as a batch or a continuous operation. The apparatus employed can be of a conventional nature and can comprise a single reactor equipped with sufficient stirring devices. Unreacted reactants, catalysts and other products of the reaction can be separated from the desired isomeric product and from one another such as by distillation and returned in whole or in part to the isomerization zone. The resultant product can be further processed as by alkylation and the like or be employed directly as a high octane gasoline blending agent. The reaction zone is preferably constructed of materials which are resistant to corrosion by the catalysts; for example, the reactor can be a Monel reactor. In a continuous system, the paraffin

The results of Table I show that n-butane conversions of about 50 percent are obtained with a butane/AsF₅ mole ratio of about 10:1 (8.2:1 to 10.9:1) over the temperature range 25 to 70° C. It is to be noted that a higher conversion (70%) was achieved by decreasing the butane/AsF₅ mole ratio to about 5/1 (4.8:1) at a temperature of 50° C.

EXAMPLE II

Hexane was isomerized to neohexane using a liquid AsF₅/HF system in the presence and absence of hydrogen in a 300 ml. Monel reactor as set forth above and described in Example I. The mole ratio of normal hexane/AsF₅ in the runs varied from 3.1:1 to 6.9:1.

Results of the isomerization of hexane are given below in Table II. The molar ratios of HF/AsF₅ used in runs 1-7, respectively, were the following 42.4, 86.1, 47.1, 42.4, 42.4, 42.4 and 38.5.

* 2,2-DMB is 2,2-dimethylbutane (neohexane); DIP is 2,3-dimethylbutane (diisopropyl); 2-MP and 3-MP represent 2-methylpentane and 3-methylpentane, respectively.

reactant can be sprayed into a column of the liquid catalyst.

EXAMPLE I

Normal butane was isomerized to isobutane with a liquid phase AsF₅/HF catalyst utilizing a Monel reactor.

The procedure for carrying out the isomerization in a Monel reactor is set forth below.

A 300 ml. Monel reactor under dry nitrogen flow was cooled in ice and charged with liquid HF and paraffin before metering in the desired weight of gaseous arsenic pentafluoride. The capped reactor was equipped with a pressure gage, valves and thermocouple. The reactor was maintained in a thermostated Eberbach reciprocating shaker-water bath under specified reaction conditions.

Workup involved cooling the Monel reactor in Dry Ice-acetone and then rapidly pouring the cold mixture into a polyethylene separatory funnel. The upper hydrocarbon layer was drained under nitrogen into a Fischer-Porter Aerosol compatibility bottle containing about five grams of potassium carbonate and cooled in a Dry Ice-acetone bath. The bottle was quickly capped with a head bearing a pressure gage and a silicone septum for withdrawing samples for glc analyses. Results are reported in terms of selectivities based on the glc analyses.

The results of the normal butane isomerization are given below in Table I:

TABLE I
(Reaction of n-butane with AsF₅ in HF *)

* 50 ml. HF used in each experiment in a 300 ml. Monel reactor, and the molar ratios of HF/AsF₅ used in runs 1-6, respectively, were the following: 56.8, 50, 50, 44.6, 22.3, and 50.

drocarbon phase was thus circulated through the dense stationary acid phase.

Immediately following the reactor was a valving system for sample withdrawal as the reaction progressed. Samples were withdrawn by an ordinary 1-ml. serum syringe fitted with a 6-inch needle. Samples for glc analysis were transferred to vials at Dry Ice temperature containing potassium carbonate.

The total hydrocarbon phase was freed of acids by passing the liquid through a sodium fluoride tube and then bubbling through a 20 percent KOH scrubber and drying the effluent over 4A molecular sieves. The effluent was collected in a bomb. All valves and tubing which were in contact with HF were made of Monel and the others were stainless steel.

Results of the normal hexane isomerization using the spray nozzle reactor system are tabulated below in Table III:

2. A process according to claim 1 wherein the hydrocarbons are contacted in liquid phase under isomerization conditions with a mole ratio HF/AsF₅ ranging from 400:1 to 1:1 and a mole ratio of paraffin/AsF₅ ranging from 50:1 to 0.2:1.

3. A process according to claim 2 wherein the paraffin is normal butane.

4. A process according to claim 2 wherein the paraffin is normal hexane.

5. A process according to claim 2 wherein the paraffin is normal heptane.

6. A process according to claim 2 wherein the isomerization is carried out in the presence of hydrogen and with a hydrogen pressure of 30-200 p.s.i.g. when the reaction exceeds about 60 minutes to suppress cracking reaction.

7. A process according to claim 2 wherein the isomeri-

17		98.9	35.1	2.8	23.6	3.8	14.6	7.5	2.2	10.4

Isomerization was predominant to cracking as shown by sample analysis for the first 72 minutes of the reaction period.

EXAMPLE IV

Normal heptane was isomerized in a Monel reactor process as defined above in Example I and the result is shown in Table IV. The run used 10.5 mmoles AsF₅, 0.5 mole n-heptane, 50 ml. HF, and 200 p.s.i.g. nitrogen.

Isomerization reaction zone is constructed of materials which are resistant to corrosion by said catalyst.

8. A process according to claim 7 wherein said isomerization is carried out under batch conditions in a Monel reaction zone.

9. A process according to claim 7 wherein the isomerization process is carried out under continuous condition by spraying paraffin hydrocarbon into a column of liquid catalyst.

TABLE IV

Run	Mole ratio n-C ₇ /AsF ₅	Time, hours	Temp., °C.	n-C ₇ , percent conv.				Selectivities		
				C ₃	C ₄ 's	C ₅ 's	C ₆ 's	C ₇ 's	Heavies	
1	47.5	3.5	23-24	96	2.6	32.1	25.2	18.6	8.2	13.3

The data show the isomerization of C₇ to the extent of 8.2 percent selectivity. The balance of the product resulted from cracking.

I claim:

1. A process for the conversion of normal paraffins to isoparaffin hydrocarbons which comprises isomerizing normal paraffins having from 4 to 7 carbon atoms to skeletal isomers containing the same number of carbon atoms by contacting the paraffins under isomerization conditions with a liquid phase AsF₅/HF catalyst.
